UNITED STATES PATENT OFFICE.

MERVIN C. JOHNSON, OF LOYALTON, CALIFORNIA.

LUMBER-PILENG JACK.

Application filed November 30, 1926. Serial No. 151,745.

This invention relates to devices used for jacking up and piling pieces of lumber and the general object of the invention is to provide a device of this character whereby lumber may be handled in a yard or mill to permit the lumber to be piled and stacked.

A further object is to provide a device of this character comprising a bar having means at one end whereby it may be inserted between the boards of a pile of lumber, the other end of the bar having a rotatable member thereon upon which a board may be rested, turned, and elevated so that a man upon the pile of lumber can grasp the board and drag it to the right place for piling.

My invention is illustrated in the accompanying drawings wherein:—

Figure 1 is an elevation of my improved lumber jack showing it engaged with a pile of boards, the boards being in section;

Fig. 2 is a top plan view of the jack;

Fig. 3 is a section through the head of the jack.

Referring to these drawings 10 designates a bar which is preferably of metal and which, if made of metal, is twisted at its middle so as to provide a flat portion 11 pointed at the end or tapered so that it may be inserted between the boards of a pile of lumber and provide a relatively elongated portion 12 disposed at right angles to the portion 11 and terminating in an eye 13. The upper surface 14 of this eye is disposed below the upper edge face of the portion 12. Resting upon the seat so formed is an annular cup-shaped member or head 15 having a lower web 16 through which passes a bolt 17, the head of the bolt bearing loosely against the bottom of the cup-shaped member, and the opposite end of the bolt being screw-threaded for engagement by a nut 18, the corner of which is rounded off. The cup-shaped member 15 is capable of free rotation upon the bolt and the upper edge of this cup-shaped member is beveled at 19 and formed in its upper edge with serrations 20.

Lumber in a yard is designed to be piled or stacked upon foundations and when first starting to pile on one of these foundations, the bar 10 is stuck in one of the posts of the foundation and the top rests against the load of lumber. The boards are then placed on this bar and jacked around to the man on the foundation. After a certain amount of

lumber has thus been stacked, the bar is stuck into the pile between the boards as illustrated in Figure 1, and the lumber is then jacked up to the man on the pile. By putting the bar in between the stacked boards, a piece of lumber, as for instance, a board, can be shifted onto the head 15 and then one end of the board may be depressed, which will raise the other end up to the man on the stack and by making this head rotatable, it is obvious that the board may be swung around into any direction desired. The man on the pile takes this board and drags it into its right place with the help of the man on the truck, ground or the car from which the lumber is being unloaded. By having the head 15 made with teeth, the board cannot slip, and yet the teeth will not mar the board as does the ordinary loading pin used today in lumber yards for the purpose of stacking boards. The teeth, therefore, are for the purpose of keeping the board from slipping while jacking up on the pile but these teeth do not mar the board for the reason that the toothed member or head turns as the board is turned. In jacking up, the board also may rest upon the upper edge of the portion 12. The rounded nut 18 is to be used for the board to rest on when first starting to build the pile of lumber, the bar being turned upside down.

It will be seen that the main object of this invention is to provide a device of the character stated whereby lumber may be handled in a yard or mill to permit the lumber to be piled and stacked without marring the lumber. The lumber piling jack which I have devised does not mar a board to such an extent that it causes a defect in grading after it is dried or ready for commercial use as the mark made by the jack will easily surface out or the planer will take off sufficient when surfacing the board.

I claim:—

1. A jack for piling lumber comprising a bar having an eye at one end, an annular cup-shaped member supported upon the eye and projecting above the bar, and a bolt loosely holding the member in place but permitting its rotation.

2. A jack for piling lumber comprising a bar having an eye at one end, an annular cup-shaped member supported upon the eye and projecting above the bar, and a bolt loosely holding the member in place but per-

mitting its rotation, the cup-shaped member being upwardly beveled at its upper edge and toothed.

3. A jack for piling lumber comprising a bar having an eye at one end, an annular cup-shaped member supported upon the eye and projecting above the bar, a bolt loosely holding the member in place but permitting its rotation, the cup-shaped member being upwardly beveled at its upper edge and toothed, and a nut engaging the lower end of the bolt, the nut having rounded edges.

4. A jack for piling lumber consisting of a bar twisted at its middle to provide a horizontal portion tapered whereby it may be inserted between the boards of a pile of boards and to provide a vertical portion terminating in an eye, the upper edge face of the eye being below the upper edge face of the bar, an annular cup-shaped head resting upon the upper end of the eye, and a

bolt passing through the head and through the eye and holding the head in place but permitting its free rotation.

5. A jack for piling lumber consisting of a bar twisted at its middle to provide a horizontal portion tapered whereby it may be inserted between the boards of a pile of boards and to provide a vertical portion terminating in an eye, the upper edge face of the eye being below the upper edge face of the bar, an annular cup-shaped head resting upon the upper end of the eye, and a bolt passing through the head and through the eye and holding the head in place but permitting its free rotation, and a nut engaging the bolt, the nut having rounded outer edges.

In testimony whereof I hereunto affix my signature.

MERVIN C. JOHNSON.
